UNITED STATES PATENT OFFICE

2,434,927

ANTENNA SYSTEM FOR DEFINING A BLIND
APPROACH PATH

Louis John Heaton-Armstrong, London, England, assignor, by mesne assignments, to International Standard Electric Corporation, New York, N. Y., a corporation of Delaware

Application October 15, 1943, Serial No. 506,301
In Great Britain November 10, 1942

Section 1. Public Law 690, August 8, 1946.
Patent expires November 10, 1962

5 Claims. (Cl. 250—11)

1

The present invention relates to a radio beacon for radio guiding systems of the kind in which a field distribution or field strength pattern is commutated or keyed so as to produce complementary signals to the right and left of the course respectively, and on the course a continuous dash or no signal and is an improvement in or modification of the radio beacon system described and claimed in our co-pending British application No. 10700/42.

An object of the invention is to provide a system which will produce a narrower path or beam width than is obtainable by the three fed antenna arrangements described and claimed in our co-pending British application No. 10700/42. The beam width may be defined as the angle subtended at the antenna by two points one on either side of the equi-signal line where the ratio of the fields from the two overlapping patterns has a given ratio, usually taken as 5%.

According to the present invention a radio beacon of the kind hereinbefore specified comprises a central antenna and a group of antennae in alignment on each side of said central antenna, the groups of antennae being fed with currents whose phases are of opposite signs (leading or lagging) with respect to the current in said central antenna and means for reversing the sign of the phase (from lead to lag or vice versa) of the current in the central antenna with respect to the currents in the groups.

The invention will be better understood from the following description taken in conjunction with the accompanying drawings, in which

Fig. 1a shows schematically the three fed antenna system;

Figs. 1b, 1c, 1d and 1e are field strength diagrams;

Fig. 2a shows schematically the antenna system according to the present invention;

Figs. 2b and 2c are field strength diagrams corresponding to Figs. 1b and 1e but of the system shown in Fig. 2a;

Figs. 3a and 3b are field strength diagrams of a system according to the invention in which the current in the two antennae adjacent the central antenna is 4I, that in the central antenna 10I and that in each of the other antennae is I; and

Fig. 4 shows diagrammatically a suitable keying unit.

In order to bring out the invention clearly a comparison of a system according to the invention will be made with the three antenna system of application No. 10700/42.

2

As a comparison a particular case is worked out for a system according to the invention six wavelengths wide which gives a beam width of .115° and the field strength on the equi-signal line is 14.5 db. higher than that for the 3 fed antenna system with aerial spacing of .475 wavelength.

Consider three antennae A, B and C as in Fig. 1a fed with currents in phase relationship 10. 180°, 90° and 0° as indicated by the arrows.

If we move round the antenna B and measure the phase and magnitude of the field from A and C we shall find that the resultant field from A and C will always be either in phase or 180° out of phase with that from antenna B. The field strength is shown in Fig. 1b for the antenna B and for the resultant of A and C. The number of lobes produced by A and C is determined by the spacing of antennae A—B and B—C, two complete lobes being produced by a spacing of .25 wavelength as shown at Fig. 1b. Fig. 1c shows the resultant field strength diagram for the three antennae, the fields being added in curve 1. In curve 2 the phase of A and C has been changed by 180°. These are the two well-known overlapping field patterns which give an equi-signal path at 0° and 180° as shown, but the width of the beam is not as small as desired.

Figs. 1d and 1e show the similar curves but with a spacing between the antennae of more than one wavelength. It will be seen that there are ten equi-signal paths altogether (the same number as the number of lobes). Note also that each alternative lobe is of reversed phase and it is this reversal of phase that causes the unwanted equi-signal paths. Hence whilst a narrower beam may be obtainable by increasing the spacing between the antennae, false paths are introduced.

40 Consider now an antenna system comprising two groups of antenna A1 . . . A12 and C1 . . . C12 fed 180° out of phase and a central antenna B fed at 90° as shown in Fig. 2a.

If we proceed round this antenna system we shall find that the lobes adjacent to 0° and 180° are larger than any others and that the lobes of reversed sign to these large lobes are much smaller and if the number of antennae n in each group is very large and d/λ is small where d is the distance between two adjacent antennae and λ the operating wavelength, these lobes will become vanishingly small.

This condition can be seen vectorially in Figs. 2b and 2c. Fig. 2b shows the field vectors starting to close in and their resultant is OY which

is the resultant of OX and OZ which are the resultants of each group of vectors due to the respective groups of antennae. Fig. 2c shows the case after the vectors due to each group has made a complete circle. If n is not large these vectors will have a small resultant as shown at OQ which is in reverse phase to OY (Fig. 2b).

By increasing the current in the aerials $A1$ and $C1$ adjacent to the centre one B , the resultant can be made always to have the same sign, so that there are no negative lobes and therefore no false courses. A particular case for $n=12$, $d/\lambda=1/4$ is shown in Figs. 3a and 3b. Here the aerial currents are in the following relative values, 10 for the central antenna B , 4 for the two aerials $A1C1$ adjacent to B , and 1 for the remainder $A2-C2$. In Fig. 3a, curve 1 is the curve of field strength distribution due to the centre antenna B , and is linear. Curve 2 shows the field strength distribution due to additional current strength in the antennae $A1C1$ adjacent the central antenna and curve 3 shows the field strength distribution due to the groups of antennae all with equal currents.

In Fig 3b the continuous line curve shows the sum of the curves 1, 2 and 3 of Fig. 3a; the broken line curve shows the difference between the sum of curves 2 and 3 of Fig. 3a and of curve 1, (i. e., $2+3-1$ it being assumed that the phase of field represented by curve 1 is reversed).

The line of intersection OX of these two field distribution curves in Fig. 3b then defines the desired course, and it will be observed that these curves cross each other at only one point, namely, on the line OX , and thus no false courses are defined.

The antenna system may be treated mathematically as follows:

1. Take field pattern as centred on B , and of phase corresponding to the field set up by an aerial at B energised with the reference phase ϕ .

2. Consider the antennae other than B as operating in pairs $A1-C1$, $A2-C2$, $A3-C3$, etc. A_n-C_n spaced apart $2nd$ and having equal currents.

3. The field set up in the direction θ to the antenna alignment by any pair of aerials will be the sum of two vectors, of equal amplitudes, but of phases

$$\left(\phi - \frac{2\pi nd}{\lambda} \sin \theta \right)$$

and

$$\left(180^\circ - \phi + \frac{2\pi nd}{\lambda} \sin \theta \right)$$

giving a resultant of phase $(\phi-90^\circ)$ and amplitude

$$2KI \sin \frac{2\pi nd}{\lambda} \sin \theta$$

where K is a constant for any particular distance.

4. The field produced by all the antennae is thus

$$2KI \left(\sin \frac{2\pi d}{\lambda} \sin \theta + \sin \frac{4\pi d}{\lambda} \sin \theta + \dots + \sin \frac{2n\pi d}{\lambda} \sin \theta \right) =$$

$$2KI \frac{\sin \frac{\pi nd}{\lambda} \sin \theta \cdot \sin \frac{\pi(n+1)d}{\lambda} \sin \theta}{\sin \frac{\pi d}{\lambda} \sin \theta}$$

If this expression is plotted against θ it will be found to change in sign and magnitude but if n is large and d/λ is less than $1/2$ the expression

is nearly always positive a typical example being shown in Fig. 3a curve 3 in full line.

If now the currents in the two antennae $A1-C1$ adjacent to the central antenna B are increased so that the current is $I+I_1$ in each, the field produced by the two groups of antennae is

$$2KI \frac{\sin \frac{\pi nd}{\lambda} \sin \theta \cdot \sin \frac{\pi(n+1)d}{\lambda} \sin \theta}{\sin \frac{\pi d}{\lambda} \sin \theta} + 2KI_1 \sin \frac{\pi d}{\lambda} \sin \theta$$

By choosing I_1 sufficiently large the above expression will not change sign between $\theta=0^\circ$ and 180° and between 180° and 360° and no false courses will therefore be obtained.

Less than 180° phase change may be used for keying if preferred thus simplifying the keying problem by requiring only a single contact-keying device. If, for example 90° phase change is used the phase of the antenna currents in this case will be $0^\circ 45^\circ 180^\circ$ for outer group, central antenna and outer group. On keying the phase of the central antenna B would be changed to 315° . In the case utilising dipole antennae keying is effected by shunting a reactance across the central dipole B .

All the antennae may be fed from the same source, from a common junction point in a transmission cable and the length of the line from

30 the said junction point to the central antenna B is made an odd number of quarter wavelengths of the operating frequency, and the lines to the other antennae have corresponding electrical lengths with respect to the antenna spacing and desired phase of the currents in the antennae.

35 Then since the length of line to the central antenna is an odd number of quarter wavelengths long, the effect of the reactance across the central dipole is to change the phase of the current fed to that dipole. By using a reactance equal in magnitude to the antenna resistance, and by changing the reactance from capacitive to inductive and vice versa, a phase change of 90° is obtained whilst obtaining a constant current in 45 the antenna.

A suitable keying unit is shown in Fig. 4. This unit comprises an adjustable inductive loop $L4$ of, for example 70 ohms impedance and a capacity $C5$ of 140 ohms impedance which is placed 50 in series with the inductance. The relay $REL1$ when operated short circuits the condenser $C5$ by closing the "make" contact $r1$. This converts the impedance across the dipole from 70 ohms capacitive reactance to 70 ohms inductive reactance. $C6$ is a blocking condenser to prevent the relay short circuiting its operating current. $L5$ is a choke coil to keep the radio frequency energy from the relay winding W .

The transmitter T feeds a line TD by means of 60 the transformer TR having tuned primary and secondary windings. $L1, C3$ is a circuit for suppressing parallel currents on the line TD ; capacities $C1, C2$ and $C4$ and inductances $L2, L3$ form a network for feeding the operating current from supply S to the relay $REL1$ along the line, thus eliminating the requirement of a separate cable. The keying mechanism is represented as a key K , and connects the source S to the line TD through the inductances $L2, L3$. The key K may of course 65 be any suitable switching device, for example, mechanical, electromagnetic or electronic, well known in the art, and in normal cases would be automatically operated.

Whilst a specific embodiment of the invention has been described by way of example, other em-

bodiments of the invention will occur to those skilled in the art and which fall within the scope of the appended claims. For example, the phase of the currents in the groups of antennae may be changed and the phase of the current in the central antenna would then be kept constant.

What is claimed is:

1. A beacon for radio-guiding systems of the type in which field distribution of pattern is commutated, so as to produce complementary signals to the right and left of the course respectively and to produce on the course a continuous signal, including a central antenna and other groups of antennae located in alignment on each side of said central antenna, means for feeding the respective groups of antennae with currents the phases of which are of opposite signs with respect to the current in said central antenna, means for reversing the sign of the phase of the current in said central antenna with respect to the currents in said other groups, and means for making the strength of the currents in the antennae of said groups nearer said central antenna relatively greater than in the other antennae of said groups, and of such energy value as to eliminate any reversal in sign of the field distribution around the system.

2. A radio beacon as claimed in claim 1, including additional means for causing the phase angle of the current in said central antenna to be at 45° with respect to the current in one of said outer antenna groups and means for changing said phase angle by 90° so as to change said phase angle from a lead to a lag and vice versa.

3. A radio beacon guiding system of the type employing phase reversal of at least one antenna of a plurality thereof, wherein said antennae are

dipoles and there are included means comprising an inductance of the same impedance magnitude as the resistance of the center dipole and a capacitor connected in series therewith and having

5 a capacity of twice said impedance magnitude, said inductance being connected in shunt across the center dipole and wherein there are provided further means for alternately short circuiting said capacitor, so as to render the said dipole alternately capacitative and inductive, thereby causing the phase angle of the current in said central antenna to be at 45° with respect to the current in one of said outer antenna groups and to change by 90° upon operation of said short circuiting means.

10 15 4. A radio beacon as claimed in claim 3, wherein in said short circuiting means comprises a single "make" and "break" contact relay.

20 25 5. A radio beacon as claimed in claim 3, including also a line feeding to the center dipole current to be radiated, an electromagnet for operating said short circuiting means and located at said dipole, and means for feeding exciting and controlling current to said electromagnet over said dipole feeding line.
